UNITED STATES PATENT OFFICE.

LUCIEN AUGUSTE JOSUÉ LEDUC, OF TOURS, FRANCE.

APPARATUS FOR RAISING SUBMARINES AND SUBMERSIBLES.

1,114,155.

Specification of Letters Patent.

Patented Oct. 20, 1914.

Application filed March 26, 1912. Serial No. 386,407.

To all whom it may concern:

Be it known that I, LUCIEN AUGUSTE JOSUÉ LEDUC, a citizen of the Republic of France, and a resident of the city of Tours, Indre-et-Loire, France, have invented new and useful Improvements in Apparatus for Raising Submarines and Submersibles, which improvements are fully set forth in the following specification.

This invention has for its object to provide apparatus applicable to submarines and submersibles which in case of a disaster, shall give an indication as to the position of the sunken vessel, and shall also render it possible to refloat the said vessel within a minimum period of time by facilitating the passing of cables under the hull of the vessel, without necessitating the coöperation of divers, who, however, are useless at certain depths.

The improved apparatus consists substantially of a plurality of buoys or floats connected two by two by a chain or cable or other similar linking device of suitable length which is guided or held in or below the submarine, the buoys being kept in engagement on the vessel and being capable of being released at will by the disengaging operation in such a manner as to rise to the surface of the water.

The buoys on reaching the surface of the water, indicate the position of the sunken vessel, and their connecting means which forms a loop underneath the vessel, can then be utilized for fastening and passing chains or cables underneath the vessel for raising the latter.

Two embodiments of this invention are illustrated by way of example in the accompanying drawings in which:

Figure 1 is a diagrammatic vertical cross section of a submarine, Fig. 2 is an elevation of a detail drawn to a larger scale. Fig. 3 is a view drawn to a similar scale of the submarine when sunk, illustrating the manner in which its position is indicated by the operation of this invention, Fig. 4 is an enlarged sectional elevation of a modification, Fig. 5 is a side view of the construction shown in Fig. 1, and shows means for maintaining and breaking the vacuum in the tubes hereinafter referred to.

According to this invention the hull of the submarine is provided internally or externally—in the latter case in such a manner as not to increase appreciably the resistance

to the progress of the vessel through the water—with tubes 1 of any desired number and section, spaced at suitable intervals along the length of the vessel, and conforming as closely as possible to the contour of the hull.

A vacuum is formed and maintained in all of the tubes 1, by a pump 12, (see Fig. 5) connected with the pipe 13, which communicates with the interior of the tubes 1 through the openings 2. Suitable cocks 14 are provided in the pipe 13, and are adapted when any one of them is opened, to permit air under pressure or surrounding water to rush into the tubes 1 and break the vacuum. While the vacuum exists, the buoys are firmly held against the openings of tubes 1, which are closed air-tight thereby. The starboard and port buoys of each tube are connected together by a cord 4 that extends the whole length of the tube. This cord is attached firmly to the point of the cone 5 of each buoy and it is coiled spirally around the buoy to the top thereof.

The cocks 14 in practice are to be located inside the submarine at such places that they can be readily operated in case of accident. When the cocks 14 are opened so as to admit either air under pressure or the surrounding water the floats will immediately rise to the surface of the water and thus unwind the cord 4, but when the cocks are closed, the floats will remain in position, even though the vessel be submerged.

Fig. 3 shows clearly the manner in which the sunken vessel can be raised. One of the buoys, for instance the port buoy is unfastened and in its place there is attached one end of a long chain or cable which is then drawn through the tube 1 by hauling on the starboard buoy. In this manner the cord which connects the two buoys together by passing through the tube 1, can be replaced by a very strong chain or cable, capable of conforming to the curvature of the tube. Naturally such strong chains or cables cannot be attached directly to the cord fastened to the buoys, but to this cord there is attached a stronger cord and so on, until to the last cord a cable, and to this cable a sufficiently strong chain is attached which can be quickly done by trained men having the necessary materials at hand.

The buoys can hold a great length of cord if it is wound in superposed layers.

A special adhesive which is dissolved very

5 rapidly by contact with water is used for keeping the cord 4 wound tightly and regularly on the buoys so long as the latter close the tube. The adhesion of the cord 4 upon the cones 5 may also be secured by providing the said cones with grooves like those of a winch barrel.

10. Whatever may be the number of tubes 1 in a submarine numerous cocks are provided at all stations in the vessel within easy reach of the crew. The opening of any single one of these cocks is sufficient to allow air or water to enter the tubes and cause all the buoys to rise to the surface of the water.
15. It is obvious that mechanical devices adapted to be released by suitable mechanism might be employed instead of a vacuum for the purpose of holding the buoys in position.
20. In the modification shown in Fig. 4, the buoys 2 are provided each with an eye 6 through which extends a rod 7 which is continued through a stuffing box 8 in the side of the tube 1 in the form of a piston rod of 25 a piston 9 working in a cylinder 10. 11 is a pipe for supplying compressed air to the cylinder 10. The stroke of the piston 9 is long enough to withdraw the rod 7 completely from the tube 1 when the apparatus 30 is released, so that the said rod may not hinder the passage of the lifting chains or cables through the tube 1.

It is to be understood that the tubes 1 may be dispensed with, and that the buoys or

floats may be held against the hull of the 5 submarine by any suitable mechanical devices, the cords being passed through rings fixed to the hull.

What I claim is:—

In apparatus for indicating the location 40 of a sunken submarine, the combination with the hull of the submarine of an air-tight tubular guideway open at each end extending around and up along each side of the hull to points of the upper part thereof, a pair 45 of buoys normally closing the respective open ends of said tubular guideway, a flexible tensile member 50 passing through said tubular guideway, fastened at its respective ends to said buoys, and having a sufficient length of its portion adjacent to each of said buoys coiled on the said buoy, means for producing a vacuum in said tubular guideway, and means for enabling the crew to destroy 55 said vacuum therein, whereby in case of the vessel sinking, the crew by destroying the vacuum in said tubular guideway, will enable the buoys to rise to the surface of the water by their natural buoyancy, as set forth.

In testimony whereof I have signed this specification in the presence of two subscribing witnesses.
